GRINDING MACHINE WORK SIZING
MECHANISM

Carl G. Flygare, Worcester, and Frank A. Helstrom, Lexington, Mass., assignors to Norton Company, Worcester, Mass., a corporation of Massachusetts

Application September 23, 1943, Serial No. 503,514

7 Claims. (Cl. 51—165)

This invention relates to grinding machines and more particularly to the wheel feeding and truing mechanisms of a grinding machine.

Various problems are involved in grinding duplicate cylindrical surfaces, and particularly on a single piece of work, where it is often necessary to true the grinding wheel before the several work surfaces have been finished. For example, the hub of an airplane propeller blade may have a set of ball raceways ground thereon by means of a formed grinding wheel. Such a wheel requires frequent truing in order to maintain its shape. When the wheel has been trued, it is necessary to feed the grinding wheel forward to a new final position in order to size the work as required. Measurement of the work size for this purpose is often difficult and time wasting. Moreover, various types of apparatus used for truing the grinding wheels of standard cylindrical grinding machines are not applicable for truing the wheel used for grinding the hub of a propeller blade because of the necessity for leaving the blade in position until all of the raceways have been ground. For example, it is customary to true the wheel at the point of contact with the work, such as in a plain cylindrical grinding machine in which the wheel is run off the work and against the diamond adjacent to the end of the work where the diamond is positioned in alignment with the grinding line of contact. This construction is not feasible in a machine of the type shown in the drawings or in other types of grinding machines where the grinding wheel must be backed off to true the work before it grinds a second surface on the same work piece.

The primary object of this invention is to overcome such problems as these and to provide a grinding machine with a wheel feeding mechanism in association with a truing device and indicator mechanism which insures that two work surfaces may be ground to identical radial dimensions before and after the grinding wheel has been trued.

A further object of the invention is to provide a truing and indicating mechanism which is so constructed and arranged that an indicating gauge may be used once and for all to indicate the final position of the grinding wheel when the work has been ground to the required size, and whereby the grinding wheel may be fed forward after a truing operation to a point indicated by that single dial setting.

A further object of the invention is to provide a grinding machine in which an indicating mechanism is so constructed in association with a wheel

truing device that the relation of the indicating mechanism to the wheel feeding mechanism remains the same during the life of the grinding wheel, and wherein the indicator may be set to a given scale marking after the machine is set up for a grinding operation and the indicator need not be changed when the grinding wheel is trued or during the period of grinding duplicate work diameters. Further objects will be apparent in the following disclosure.

This invention is applicable to the various types of grinding machines, but it is herein illustrated as applied to a machine especially adapted for grinding a set of parallel spaced raceways on the cylindrical hub of an airplane propeller blade, as is required for feathering the blade during its operation.

Referring to the drawings:

Fig. 1 is a vertical elevation of the machine, with parts broken away to show details of construction;

Fig. 2 is a top plan view of the machine with parts broken away to show the work supporting slide and elevating mechanism;

Fig. 3 is an enlarged sectional detail of the wheel truing and indicating mechanisms;

Fig. 4 is a vertical sectional view on the line 4—4 of Fig. 3;

Fig. 5 is a view taken on approximately the line 5—5 of Fig. 3, parts being broken away for clarity of illustration; and

Fig. 6 is a fragmentary detail showing the truing tool slide and operating mechanism.

In accordance with the illustrated embodiment of this invention, a grinding wheel is mounted on a slide arranged to feed the wheel into the work. A diamond truing tool is mounted on a second slide carried by the first slide, and it is arranged to feed the diamond forward against the wheel at a point which is 180° from the line of grinding contact with the work. A dial gauge or other suitable indicator is mounted on a stationary portion of the base. The position of the line of grinding contact with the work may be indicated by suitably setting this gauge, and the extent of forward feed of the wheel towards the work is measured thereby. The truing tool is connected to the dial gauge by means of a lever of the first class which is pivoted on the lower slide. One arm of this lever is connected to the upper slide carrying the diamond, and the lower arm of the lever operates the dial. The two effective lengths of the lever arms are exactly equal; hence the forward movement of the wheel slide to compensate for truing the wheel causes the gauge to

register the same reading for a given work size irrespective of any reduction in wheel size.

As shown in the drawings, the grinding machine comprises mechanism for supporting the propeller blade 10 in a vertical position so that it may be ground by a grinding wheel 11. The blade is mounted for rotation about the axial line of its cylindrical hub 12. The grinding wheel 11 is suitably mounted on a vertical shaft 13 which is axially parallel with the work axis. Suitable power mechanism may be provided for rotating the grinding wheel shaft, such as a standard electric motor 14 of a constant speed type. The wheel and motor shaft is supported in suitable radial and end thrust bearings, and the vertical position of the wheel is thereby accurately determined. The grinding wheel support, including the electric motor, is mounted on a wheel slide 15, which in turn is slidably mounted on suitable horizontal ways 16 on the machine base 17. The wheel is axially immovable, or not movable vertically along its axis, but it may be moved by the slide towards and from the work with its side faces lying always in the same parallel planes.

The wheel slide may be moved by suitable or standard construction. As shown, the under side of the wheel slide is provided with a half nut 18 engaging the threads of a large screw 19; and the latter is adapted to be rotated by a suitable micrometer mechanism for manually adjusting the position of the grinding wheel. The screw 19 is supported at one end on a small shaft 20 suitably mounted in bearings in the framework. This shaft carries a bevel gear 21 meshing with another gear 22 on one end of a short cross shaft which has fixed on its other end a gear 23 meshing with a further gear 24 on the micrometer hand wheel shaft. The hand wheel 25 and the associated micrometer mechanism 26 serve to turn the gear 24, and this moves the wheel slide precisely to an extent measured by the micrometer or until a stop on the micrometer strikes the pawl 27 thrown into its path. All of this may be of standard construction. The right hand end of the screw 19 is carried on a large bearing member 28 suitably mounted in the machine. This construction may be made according to the U. S. patent to Wood No. 2,294,872 of September 1, 1942. If desired, the wheel slide may be moved hydraulically by power mechanism such as that shown in the U. S. patent to Cole No. 2,283,792 of May 19, 1942.

The propeller blade or other work piece is held rigidly in a vertical position in axial parallelism with the wheel. The work is mounted to be both rotated and adjusted vertically. It is clamped by suitable mechanism in axially alignment with a rotatable, vertically adjustable support 30. This support is carried by a shaft 32 which is suitably mounted in thrust and radial bearings carried in a hollow slide casing 34. The lower reduced end 36 of the shaft 32 is slidably keyed within the hub of a pulley 37 suitably suspended in bearings 38 on the horizontal frame member 39 of the machine frame. The pulley is rotated at a desired slow rate by a belt leading from an electric or other suitable type of motor 40 mounted on the outside of the machine base.

Provision is made for moving the work vertically along its axis and relative to the grinding wheel, so that the axially immovable wheel may grind a series of parallel ball raceways. To this end, the casing 34 is provided with two aligned,

laterally projecting slide members or flanges 42 (Fig. 2) which bear against the vertical slide faces 43 formed on a wall 44 constructed as a part of the machine base. The slide flanges are held in place by means of gib 45 secured by screws to the wall 44.

The casing 34 and associated parts are supported on the top of a hollow frame having spaced, parallel side walls 47 and a horizontal bottom portion 48. The latter carries a threaded bushing 49 which is threaded onto the vertical jack screw 50 supported in suitable bearings 51 at the base of the machine. The jack screw 50 carries near its lower end a gear 52 keyed thereto. This gear meshes with a gear 53 on a suitably supported vertical shaft 54 which carries at its upper end a worm gear 55 meshing with a worm on a horizontal shaft 56 to which is affixed a hand wheel 57. By turning the hand wheel, the screw 50 will be threaded through the bushing 49 and thus will adjust the supporting frame vertically and locate the propeller blade carried thereby. The axis of the lifting screw is preferably located in vertical alignment with the center of the mass of the propeller and the supporting slide, as shown in Fig. 1. Various features of this machine are described and claimed in the copending application Serial No. 498,958 filed August 17, 1943.

The grinding wheel may be trued to the required shape by a truing mechanism of suitable construction, such as one made in accordance with the patent to Griffing #2,056,149 issued September 29, 1936. As shown particularly in Fig. 5 a diamond 60 is set to project from the end of a metal holder 61 which is slidably mounted in a swinging cradle 62 for endwise movement toward and from the grinding wheel. The slide holder 61 has a large head 63 at its outer end and a compression spring 64 is mounted between this head and a wall of a recess within the cradle and so arranged as to tend to withdraw the diamond from contact with the grinding wheel. The diamond is held forward against the grinding wheel and its slideable movement is determined by means of a form bar or cam 65 which engages a projecting tip 66 of the diamond holder 61. This form bar 65 is so shaped that as the diamond is rocked back and forth by swinging the cradle 62, the diamond 60 will be moved to shape the cylindrical surface of the grinding wheel as required to make the ball raceway groove on the propeller shaft.

Both the cradle 62 and the form bar 65 are carried on a slide 70 which is slidably mounted on a framework carried by the lower slide 18 and arranged to move the diamond toward and from the wheel. The slide has depending from its lower side two diverging arms 72 which are connected through spaced journal boxes 73 with two lower arms 74. A form bar support 76 also hangs from the slide and connects the upper and lower arms 72 and 74 at intermediate points. This support has two spaced curved ribs 77 forming a groove within which the form bar 65 is removably mounted. Various strengthening ribs 78 are arranged on the support 76 to hold the form bar rigidly in place.

The swinging cradle 62 is suitably mounted within the journal boxes 73 on end pivots 80 and 81. A handle 83 connects with one pivot and serves to rock the cradle as required. This rocking motion traverses the diamond across one wheel face. The diamond moves in and out in accordance with the shape of the form bar 65.

The slide 70 is slidably mounted on the under side of a cover 86 carried on the casing walls 87 which are rigidly mounted on the wheel slide 15. Projecting ears 88 on the cover 86 are mounted on the pivot pins 89 carried by suitable ears 90 on the casing walls. Suitable clamp bolts 91 are pivoted to the outside of the casing walls 87 and are adapted to be swung up into slots on the flanges 82 of the cover and thus clamp the cover in position. This permits the cover to be swung up and thus to move the diamond and form bar to positions where they may be removed or inspected. The slide 70 is held in position by means of gibbs 95 (Fig. 4) suitably secured, as by screws, to the under side of the cover 86. The slide 70 is made sufficiently short so that it may be moved back and forward as desired for truing the wheel.

In order that the slide may be moved manually, it is provided with an upstanding flange which is threaded to form a nut 100. This carries a screw 101 (Fig. 3), and the reduced end 102 of this screw is supported on suitable ball bearings in a housing 103 carried on the cover 86. A spiral gear 104 on the end of this shaft 101 connects with another gear 105 keyed on a shaft 106 which is suitably mounted on a bracket 107 carried by the casing walls 87. A micrometer dial 108 (Fig. 6) is arranged on the outer end of the shaft for turning the screw 101 through a measured distance and thus moving the slide that carries the diamond. By manipulating the micrometer 108 and the handle 83, the diamond may be caused to true the surface of the grinding wheel.

In the use of the machine, the grinding wheel is fed forward to grind one of the ball raceway grooves on the propeller blade. Ordinarily, the micrometer mechanism 26 is moved to set a stop carried by the hand wheel 25 at a required distance from the pawl 27, so that the grinding wheel may be fed forward until the stop engages the pawl, thus indicating that the wheel has been moved through the required number of thousandths of an inch for the grinding operation. If the wheel is trued after one of the ball raceways has been ground, then it is necessary to reset the micrometer mechanism by a distance equal to the decrease in radius of the grinding wheel when trued by the diamond.

In order to indicate the distance through which the diamond has been moved and by which the grinding wheel must be fed forward to give the same depth of cut, I have mounted a standard dial gauge 110 on a stationary pedestal 111 fixed on the machine base 17 (Fig. 1). A sliding bar 112 is suitably mounted in and slides through supports 113 projecting laterally from the wheel slide 15. This bar may contact with and operate the plunger 114 of the dial gauge. The bar 112 moves horizontally in the direction of the wheel slide movement, and any movement of the slide registers on the dial gauge. A pin 115 projecting laterally from the bar 112 rides between the yoke ends of a swinging lever 116 which is mounted on the pivot shaft 117. This shaft is suitably mounted in bearings 118 on the top of the wheel slide 15. At the inner end of this shaft is an upstanding lever arm 120. The top of this lever arm is also shaped to form a yoke, and between the fingers of the yoke rides a pin 122 which projects laterally from the form bar support 76. The pin 122 moves with the slide 70 and the diamond and therefore may serve to measure the decrease in radius of the wheel when trued. The

effective lengths of the arms 116 and 120 are made exactly the same. That is, the pins 115 and 122 are equi-distant from the axis of the shaft 117, and thus any movement of the pin 122 forward with the diamond supporting slide moves the lower pin 115 and the slide bar 112 back through the same distance. This causes the plunger of the dial 110 to move through the same distance, and thus indicate the decrease in wheel size when it is trued.

When a new grinding wheel is put into place on the machine, the zero position of the dial gauge 110 is determined and set once and for all, so as to give a required depth of cut in the work and produce the desired ball raceways. When the work position is to be changed to grind a new groove, the grinding wheel is backed away from the work, thus moving the bar 112 from engagement with the dial gauge. The work is adjusted vertically as described, and again the grinding wheel is fed forward into contact with the work and the grinding proceeds until the dial gauge again registers zero. If the wheel is to be trued, the diamond slide 70 and the pivot pin 122 are moved forward during truing, and the pin 115 and the slide bar 112 which operates the plunger of the dial move forward equally. In order that the grinding wheel of reduced size may grind to the same depth of cut, the operator 20 must now use the micrometer mechanism 26 to feed the wheel forward through the exact distance that it was decreased in radial size. The forward feeding movement of the wheel slide 15 causes the axis of the pivot shaft 117 and the pin 122 to move equally; hence the swinging arm 116 travels parallel with itself. That is, if the pin 122 has been moved forward by 5 thousandths of one inch, this moves the slide bar 112 away from the dial to the same extent. Then the wheel slide 25 must be moved up 0.005" before the dial will register zero, as before. Thus the indicating mechanism compensates automatically for a reduction in wheel size due to truing or normal wear of the wheel. This condition is brought about by the fact that the dial gauge 110 is stationary on the wheel base, the pivot shaft 117 is mounted on the lower slide 15 and the pin 122 is on the upper slide 70. Thus the lever arm 116 moves parallel with itself as the wheel slide 15 is moved 30 in and out and the dial 110 indicates the final grinding position. When the wheel is trued, the lever arm 116 tilts to a different angle and the bar 112 moves back through the same distance as represents the reduction in wheel size. Thereafter the arm 116 moves parallel with itself as the wheel slide is moved, and the latter must be moved up to an additional extent as represented by the reduction in wheel size before the dial gauge 110 will indicate zero. Hence the dial 35 shows the final grinding position of the wheel at all times, irrespective of wheel wear.

It will now be appreciated that the sizing apparatus above described may compensate for the ordinary wheel wear when the work is being sized. That is, if the wheel has worn to a smaller diameter and the diamond is moved up until it just touches the wheel, the rocking lever automatically moves the dial gauge bar 112 back through an equal distance. Then the wheel slide will have to be fed forward by that same distance to make the dial gauge register the predetermined reading, such as zero, which indicates that the work has been ground to the required final size. The forward movement of the pivot of the rocking lever is the same as the reduction in radius of

the wheel, whether caused by wheel wear or truing or both. Hence, the diamond may be moved to correspond with a reduction in wheel size, and this movement automatically requires that the wheel be fed forward through the same distance before the dial gauge will give its zero reading.

It will be understood that these general principles of work sizing are applicable to any type of grinding machine which has a grinding wheel support and a work support that are relatively movable towards each other to feed the wheel into the work. The pivot of the rocking lever is mounted on the movable support, the dial or other type of gauge employed is stationary, the gauge is operated by one arm of the lever, and the other arm is arranged to be moved in correspondence with a reduction in wheel wear.

It will also be appreciated that various mechanical equivalents may be substituted for the rocking lever with its equal arms; or other mechanical elements may be used in association to give the same results as above described. The lever or equivalent mechanism is such that the member which operates the size indicating device, such as the dial gauge, is moved through a distance that is proportional to the reduction in wheel diameter, and the parts are so arranged that the wheel must be fed towards the work through a distance which compensates for the loss in wheel size before the indicating mechanism will give the same final reading as before to indicate a given work size.

Hence, the above disclosure is to be interpreted as explaining the principles of my invention and as describing a preferred embodiment thereof and not as imposing limitations on the appended claims.

We claim:

1. A grinding machine comprising a work support, a grinding wheel, a support for the wheel, means for moving the supports relatively towards each other to feed the wheel into the work, a stationary gauge which indicates work size, a device movable forward independently of said supports to a position determined by a reduction in the wheel radius, a member for operating the gauge, and mechanism which moves said member away from the gauge by a distance proportional to the forward movement of said device and which requires feeding the wheel towards the work through a distance equal to the reduction in wheel radius so as to give a predetermined gauge reading for a given work size.

2. A grinding machine comprising a work support, a grinding wheel, a support for the wheel, means for moving said supports relatively to feed the wheel into the work, a device movable independently of said supports to touch the effective surface of the wheel at a point which is 180° from the point of work grinding contact, a stationary work size indicating gauge, a member carried by the movable support which operates the gauge, and means connecting said device and member which moves the latter away from the gauge through a distance that is proportional to the forward movement of the device as required to touch the wheel, said parts being so arranged that when the wheel is fed towards the work said member is moved forward through a distance equal to any reduction in wheel radius to give a predetermined fixed gauge reading for a given work size.

3. In a grinding machine having a work support and a grinding wheel to grind the work, a

wheel truing and work sizing mechanism comprising a grinding wheel slide, means to feed the slide to grind the work, a truing tool, a tool slide on the wheel slide for feeding the tool to true the wheel, a stationary size indicating gauge, and a lever having its effective arms of equal length which is pivotally mounted on the wheel slide, one arm being connected to move forward with the truing tool and the other arm being connected to operate the gauge, said parts being so arranged that the gauge registers a predetermined reading for a given work size irrespective of any decrease in wheel size due to truing the wheel.

4. In a grinding machine having a work support and a grinding wheel to grind the work, a wheel truing and work sizing mechanism comprising a stationary base, a wheel slide on the base, means to feed the slide to grind the work, a truing tool, a truing tool slide on the wheel slide movable to true the wheel at a point which is 180° from the grinding point, a stationary size indicating gauge mounted on the base, a lever having its effective arms of equal length which is pivotally mounted on the wheel slide, one arm being movable forward with the truing tool slide as the truing tool is fed forward to true the wheel, and the other arm being connected to operate the gauge, and means for moving the truing tool slide, said parts being so arranged that the gauge registers a predetermined reading for a given work size irrespective of any forward movement of the slides as required to true the wheel and feed the wheel to grind the work.

5. A grinding machine comprising a base, a work supporting slide, a grinding wheel, a wheel slide, means to move the work parallel with the wheel axis, means for moving the wheel slide to feed the wheel into the work, a stationary indicating gauge mounted on the base, a lever pivotally mounted on the wheel slide which has its effective arms of equal lengths, one arm being connected to operate the gauge, and means whereby the other arm may move in correspondence with a reduction in wheel size, said parts being so arranged that the gauge registers a predetermined reading for a given work size irrespective of any decrease in wheel size.

6. A grinding machine comprising a base, a work slide thereon, a rotatable work support on the slide, a grinding wheel, a grinding wheel slide on the base which is movable to feed the wheel into the work, a truing tool, a mount for moving the tool forward to true the wheel at a point which is 180° from the point of work grinding contact, a size indicating gauge fixed on the base, a member for operating the gauge, a lever having its effective arms of equal lengths which is pivotally mounted on the wheel slide, a connecting means whereby one arm moves forward with the truing tool, the other lever arm being connected to move said member away from the gauge through a distance equal to the forward movement of the tool, and means for moving the wheel slide forward which moves the lever and truing tool in a fixed relation so that the gauge automatically registers a predetermined reading for a given work size irrespective of any indeterminate reduction in wheel size.

7. A grinding machine comprising a base, a work slide mounted thereon for vertical slidable movement, a rotatable work support on the slide, a grinding wheel having a vertical axis, a wheel slide carrying the wheel and movable to feed the wheel horizontally towards the work, a size indi-

cating gauge fixed on the base, a truing tool, a mount for moving said tool to true the wheel at a point which is 180° from the point of work grinding contact, a lever pivotally mounted on the wheel slide which has its effective arms of equal lengths, means whereby one arm moves forward with the truing tool, and a member moved by the other arm which operates the

gauge and is moved away from the same when the tool moves forward, said parts being so arranged that the gauge gives a predetermined reading for a given work size irrespective of any reduction in wheel size.
